UNITED STATES PATENT OFFICE.

EDWARD H. GOVE, OF BIDDEFORD, MAINE.

TANK-SIPHON.

1,353,230.

Specification of Letters Patent. Patented Sept. 21, 1920.

Application filed March 27, 1916, Serial No. 86,913. Renewed March 22, 1920. Serial No. 367,892.

To all whom it may concern:

Be it known that I, EDWARD H. GOVE, a citizen of the United States, residing at Biddeford, in the county of York and State 5 of Maine, have invented certain new and useful Improvements in Tank-Siphons, of which the following is a specification.

This invention relates to improvements in tank siphons. It is designed to produce a 10 device which will operate with absolute certainty and with the greatest ease. It is also designed to deliver a fixed quantity of liquid at each operation of the siphon. It is also designed to produce a device which is simple and inexpensive in construction.

In the drawing herewith accompanying and making a part of this application I have shown one embodiment of my invention, but the siphon action producing mechanism may be applied to any form of siphon. In said drawings Figure 1 is a perspective view of one form of siphon and its 20 operating mechanism, a portion of the short leg and tank being broken away; Fig. 2 is a detail sectional view of the mechanism which prevents the siphon action recurring before the initial action is complete; Fig. 3 is a sectional view showing the apparatus constructed for use in tanks of less depth 25 or where the lifting rod passes through the short leg; Fig. 4 is a vertical sectional view where the lifting rod passes through the side of the short leg, and Fig. 5 is a vertical detail plan view of a portion of the same.

30 Same reference characters indicate like parts in the several figures.

In said drawings 1 represents a liquid tank of any usual construction in which is mounted a long leg 2 flaring at the top as 35 seen at 3 and provided with openings 4 in the top formed by the removal of a portion of the top and sides. The leg 2 has cast thereon projections 5 which serve to give lateral support to a short leg 6, which short 40 leg may be of any suitable material, preferably of glass. In each of opposite sides of the flaring top of leg 2 is a groove 7 and in the projections 5 are grooves 8 in vertical line with groove 7. The leg 6 has an inferior vertical tongue 9 on each side adapted 45 to take into said grooves in the long leg when the short leg is placed down over the end thereof, thus holding it firmly against any movement relative thereto except up 50 and down movement. Siphon movement is

produced by means of a plunger comprising two similar plates 10 substantially rectangular in form except the inner ends which have curved recesses to embrace the long leg; and of a combined area substantially 60 equal to the interior horizontal sectional area of the short leg, the inner ends being adjacent said long leg. The plates 10 have ears 10^a in the top by which they are pivotally mounted on a pivot 11 in arms 12 of 65 a carrying frame which comprises a ring 13 and a ring 14 spaced apart downwardly therefrom and united by links 15, which frame and links may be cast in one piece if desired. It is movable up and down 70 relative to and upon leg 2 and may be raised by a chain 16 attached to the lower ring. The plates are pivotally mounted so that gravity will cause them to return down as soon as the siphon action ceases. The plates 75 of the plunger preferably have slightly upturned flanges 17 on the outer edges which preferably flare outwardly somewhat to ease the movement of the plunger and to better hold the liquid.

80 The operation of this form of my apparatus is as follows:

To start the siphon action the plunger is raised bodily upwardly in leg 6 lifting the liquid therein until it overflows into leg 2 85 through openings 4. As soon as the siphon action is started the operating lever may be released and the weight of the plunger will cause it to return down, the plates of the plunger being free to turn upwardly on 90 their pivots offering substantially no obstruction to the down return, the plates assuming, when down and siphon action has ceased, automatically a horizontal position. It will be understood that the rising liquid 95 in the tank will turn the plunger plates automatically on their pivots to admit liquid into leg 6 to the depth of liquid in the tank.

100 It sometimes happens that when the inlet to the tank is rapid the inflowing liquid refills the tank above the siphon intake before the siphon action is completed and a supplemental siphoning takes place. To prevent this unnecessary waste of liquid I secure to the top of leg 6 a cap 18 open into the siphon 105 chamber and mounted in said cap is a pipe 19 which extends downwardly to about the same position as the plunger plates and thence turns upwardly as seen at 20 so that the siphon action will continue until the 110

liquid in the tank is reduced to the level of the plunger plates and cannot be restored until the liquid in the tank rises again above the end 20 of the pipe on account of the 5 breaking of the siphon action by admission of air.

In Figs. 3, 4 and 5 I have shown a modification of my invention adapted for use in tanks in which the liquid is usually of less 10 depth. Here the carrying frame has only one ring and the plunger is lifted by a rod 21 extending up the inside of the short leg, one end attached to the carrying frame and the other attached to an operating lever not 15 shown. As shown in Fig. 3 this rod passes through an air tube in the short leg extending from a point intermediate the top and bottom and having an airtight union with the leg at the top. The rod has a cap 23 20 which closes the upper end of the tube and limits the downward movement of the plunger. In the form shown in Figs. 4 and 5 the short leg has an outwardly extending offset 24 extending to a point midway of the 25 leg and has an opening 25 at the top. In this case the lifting rod runs in said offset and through said opening. It is provided with a cap 23 and operates as the rod and cap does in Fig. 3. The liquid in the short leg 30 will remain under pressure until the liquid in the tank falls below the end of the tube in the one case or the upper end of the offset in the other case. Before this occurs the plunger being released will fall to its seat 35 and prevent breaking the siphon action by admission of air to the short leg.

My device may by obvious changes of form be used when the short leg is circular and may be used with various forms of 40 siphons including the bent tube form and still be within the spirit and scope of my invention.

The advantages of my apparatus are 45 many. There is a great saving of liquid, absolute certainty of operation and a perfectly free liquid and consequently rapid and efficient flushing current.

I claim:

1. In a device of the character described, a tank, a bell siphon comprising a long leg 50 and a short leg, the open top of the long leg flaring and the closed top of the short leg adjacent the open flaring top of the long leg tapering upwardly, a plunger mounted in said short leg comprising a carrying 55 frame and plates pivotally attached thereto, said frame and plates being adapted to reciprocate in said short leg and said plates to turn on their pivot points, and means for reciprocating said plunger.

2. In a device of the character described, a tank, a bell siphon comprising a long leg and a short leg, a plunger mounted in said short leg comprising a carrying frame and plates pivotally attached thereto having 65 their adjacent ends curved inwardly to embrace the short leg, said frame and plates being adapted to reciprocate in said short leg, and means for reciprocating said 70 plunger.

3. In a device of the character described, a tank, a bell siphon comprising a long leg and a short leg, a plunger mounted in said short leg comprising a carrying frame composed of two rings mounted on the long leg 75 of the siphon and spaced apart and connected by a bonding link, the upper ring positioned within the short leg and carrying pivotally mounted plates, said frame and plates being adapted to reciprocate in said 80 short leg and the plates to turn on their pivots, and means for reciprocating said plunger.

4. In a device of the character described, a tank, a siphon comprising a long leg and 85 a short leg extending down over said long leg, mutually engaging members on the inside of said short leg and on the outside of the long leg adapted to prevent all movement of the short leg relative to the other 90 except vertical movement and means for starting siphon action.

In testimony whereof I affix my signature.
EDWARD H. GOVE.
